UNITED STATES PATENT OFFICE.

CALVIN C. NEWPORT, OF DES MOINES, IOWA, ASSIGNOR TO DES MOINES INCUBATOR COMPANY, OF DES MOINES, IOWA, A CORPORATION OF IOWA.

SECTIONAL GRAIN SPROUTER.

Application filed November 10, 1921. Serial No. 514,418.

To all whom it may concern:

Be it known that I, CALVIN C. NEWPORT, a citizen of the United States of America, and resident of Des Moines, Polk County, 5 Iowa, have invented a new and useful Sectional Grain Sprouter, of which the following is a specification.

The object of this invention is to provide an improved device for the reception of 10 grain during the process of sprouting.

A further object of this invention is to provide an improved elastic or sectional device adapted to facilitate the artificial sprouting of grain.

15 A further object of this invention is to provide a sectional device of the class described, comprising a base or heating unit and a plurality of tray units adapted to contain the grain to be sprouted, the walls of 20 said tray sections being formed with air chambers so arranged as to communicate when the several sections are collocated for use.

25 A further object of this invention is to provide improved means for removably and replaceably mounting grain trays in the tray units.

30 A further object of this invention is to provide an improved top section having a hinged top portion with a specially arranged 35 stop brace and also provided with vents leading from its interior and from the air chamber or space.

A further object of this invention is to 40 provide an improved construction for glazed doors for the tray sections.

My invention consists in the construction, arrangement and combination of elements 45 hereinafter set forth, pointed out in my claims and illustrated by the accompanying drawing, in which—

Figure 1 is a front elevation illustrating my improved device. Figure 2 is a vertical section of the same. Figure 3 is a side elevation of the top section, dotted lines showing the cover in partly open position. Figure 4 is a plan of the top section. Figure 5 is a plan of the top section, the cover and trays being removed. Figure 6 is a plan of a 50 tray employed in the device. Figure 7 is a vertical section on the indicated line 7—7 of Figure 1, of one of the doors and on an enlarged scale.

In the construction of the device as shown 55 the numeral 10 designates generally a base

section, on which are removably and replaceably mounted a plurality of tray sections 11, in this instance three in number, all of which are surmounted by a top tray section 11^a provided with a cover 12 hinged thereto at one margin. The base section 10 and tray sections 11, 11^a are rectangular in plan and elevation, and the base section 10 preferably is of materially greater vertical dimension than said tray sections. The base section 10 is composed of frames formed of wooden strips 13 on which are mounted walls 14 and a bottom 15 of sheet metal, preferably galvanized. The base section 15 preferably is provided with sills 16 secured to its bottom, whereby said bottom is elevated above the supporting surface. The base section 10 is provided with a relatively large opening 17 in its front wall, and a door 18 is hinged at one side margin to a frame 70 member 19 of said wall and is adapted to partially close said opening 17 at times; as shown, however, the door 18 is of less vertical dimension than the opening 17 whereby a space is left at the bottom of the door 80 when closed for the admission of ventilation to the section and device. The door 18 also is formed with a ventilating port 20 and with a knob handle 21. A heating device such as a lamp 22, shown conventionally, is mounted in the base section 10 and rests loosely on the floor 15 thereof. A pan 23 is mounted in the upper portion of the base section 10 and is spaced at its sides from the side walls 14 of said section whereby slots or 85 passages 24 are provided leading from the interior of said base section through the top thereof, it being understood that said base section is open at its top except for the closure by means of said pan. The front wall of the base section 10 preferably is formed with a ventilating slot 25 adjacent the front of the pan 23.

90 Each tray section 11, 11^a is formed of frames 26 of wooden strips to which are attached metal side walls 27, said sections being open at their bottoms and tops, save for the hinged cover 12 of the uppermost section 11^a as above noted. The sections 11, 11^a are adapted to be mounted in series upon the base 10 and upon each other, the frames 26 resting upon the frames 13 of said bottom section or upon other frames 26 of other tray sections, the walls 27 being in alignment with the walls 14 of the base sec- 100

105

110

tion. The tray sections 11, 11^a also are formed with inner walls 28 spaced from the walls 27 whereby an air space or chamber 29 is provided extending from the bottom to top of each section on the rear and sides thereof. The inner walls 28 of the tray sections 11, 11^a are extended below the planes of the lower margins of the bottom frames 26 and outer side walls 27 of said sections, 16 said projecting portions being offset or bent inwardly from the planes of the inner walls, and being designated by the numeral 30. The projecting portions 30 of the inner walls are adapted to nest or fit snugly within the 15 walls 28 of the subjacent section, or, in the case of the lowermost of the tray sections, within the pan 23 of the base section 10. In this manner the superposed sections are held firmly in position and accidental displacement by lateral movement is prevented. When the tray sections 11, 11^a are so mounted, the air spaces 29 of said sections are continuous and communicating from the lowermost to the uppermost of said sections, and 25 the bottom of the air space or chamber of the lowermost of said tray sections communicates with the slots or passages 24 between the pan and side walls of the base section, whereby communication is provided between 30 the interior of said base section and the surrounding air spaces or chambers of all of the superposed tray sections.

The frame 31 of the hinged cover 12 preferably is composed of strips which are wider 35 than the frame strips 26 of the tray sections, and said frame members 31, when said cover is in closed position, overlie and close the upper ends of the air spaces or chambers 29.

The side and rear outer walls 27 of the 40 uppermost tray section 11^a are formed with a number of vents 32, whereby a limited circulation of air from the air spaces or chambers 29 is permitted when the cover 12 is closed. The cover 12 also is provided 45 with vents 33 to permit escape of air from the interior of the tray sections.

On the forward sides of the tray sections 11, 11^a the walls 27 and 28 are omitted so that the sections are open at said forward 50 sides except as hereinafter noted. Angle strips 34 are fixed to the inner faces of the inner side walls 28 of the tray sections and provide supports on which are slidably, 55 removably and replaceably mounted grain trays 35, two of said trays being provided for each of the tray sections 11 and 11^a. The trays 35 preferably are formed of sheet metal with perforations 36 in their bottoms, and are comparatively shallow. A stop strip 60 37 is mounted vertically across and projects inwardly from the rear wall of each tray section 11, 11^a. It is the function of the stop strips 37 to limit rearward movement of the trays 35 and prevent contact thereof with 65 the rear walls of the tray sections, whereby

an air space is formed at the rear of the device between the rear walls and trays.

Each tray section 11, 11^a is provided with a door 38 hinged at one margin to its front frame, and each of said doors is formed of 70 a rectangular frame 39, of sheet metal in which is mounted a sheet 40 of glass. I prefer to mount the glass sheets 40 in the door frames by stamping or pressing hooks 41 rearwardly from said frame (see Fig. 7), 75 the sheets 40 being received and held between said hooks and the main portions of the frames.

Each of the doors 18, 38 is formed with a short vertical slot 42 adjacent the margin 80 opposite the hinged margin thereof, and a screw eye 43 is mounted in the adjacent frame member of the section on which each door is carried. The screw eyes 43 are adapted to pass through the slots 42 when 85 the doors are closed, and when said screw eyes are turned a quarter turn so that they stand transversely of the slots they serve to prevent opening of the doors. Each of the doors 38 also is provided with a knob handle 21.

The inner walls 28 of the tray sections are spaced from the outer walls 27 thereof by means of blocks 44, or strips, as shown in Figure 5, which blocks also provide means 95 for attachment of said inner walls.

A hook brace 45 is hinged at one end to a side frame member of the cover 12 and is adapted to extend between the walls 27, 28 of the top tray section 11^a, said brace being 100 formed with a hook 46 on its opposite end. The brace 45 extends between studs or nails 47, 48 carried by the adjacent top frame member 49 of said top section 11^a and extending across the space between the walls 105 27, 28 of said section. When the cover 12 is moved to its furthest limit the hook 46 of the brace engages one of the studs or nails 47, 48 and prevents withdrawal of said brace from the space between the walls and 110 also limits opening movement of the cover and serves to support said cover in open position, in a position inclined to the rear of the vertical. As the studs or nails 47, 48 are spaced only sufficiently for free travel of 115 the brace 45 between them, the engagement of one of said studs or nails by the hooked end of said brace is insured.

In practical use the device is assembled as 120 shown and grain to be sprouted, particularly for use as poultry food, is placed in the trays 35. The grain is sprinkled with water as desired, and drip from the upper trays is received in turn by the underlying trays and finally by the pan 23. Heat is furnished by the lamp 22 and heated air from the interior of the base section 10 rises through the air spaces or chambers 29 of the walls of the tray sections and insulates and protects the 125 interior of said tray sections from influence 130

of cold atmospheric air, and a restricted circulation of air to and from the device is permitted by the vents 32 in the outer walls of the top section. The heating of the base 5 section also causes an evaporation of water in the tray or pan 23, and heated, moist air rises from said base section through and around the perforated trays, and grain therein is caused to sprout and grow rapidly. 10 The condition of the sprouted grain may be viewed at any time through the glazed doors 38, and any of the trays may be removed, by endwise movement on the strips 37, by opening the doors 38. The capacity of the device 15 may be increased by adding other tray sections 11, or diminished by removing certain of said sections, so that the device may be adjusted in size and capacity to the needs of each user. 20 I do not desire to be understood as limiting myself to the precise construction herein shown and described, as various modifications, within the scope of the appended claims, may be employed without departing 25 from the spirit of my invention.

Particular emphasis is laid upon the advantage of employing this device for the sprouting of grain, such as oats, for use as feed for chickens during the winter season; 30 thus providing during such winter season the kind of food most needed by the fowls and which without a device of this kind it is impossible to procure for them.

I claim as my invention—

35 1. A grain sprouter, comprising a base section adapted to contain a heating device, a plurality of tray sections separately formed and adapted to be mounted in series upon said base section, grain trays mounted 40 in said tray sections, said tray sections being formed with double walls the air spaces of which communicate with the air spaces of adjacent sections, the air spaces of the lowermost tray section communicating with 45 the interior of the base section, and a movable top for the uppermost tray section, said top when closed forming a closure for the upper ends of said air spaces.

2. A grain sprouter, comprising a base section adapted to contain a heating device, a 50 plurality of tray sections separately formed and adapted to be mounted in series upon said base section, said tray sections being formed with double walls whereby air spaces are formed, which air spaces are open at their upper and lower ends, the bottom of the air spaces of the lowermost tray section communicating with the interior of said base section, the bottoms of the inner walls of said tray sections being projected below the planes 55 of the bottoms of the sections and adapted to nest within the walls of the next underlying sections, and a top for the uppermost tray section.

3. In a grain sprouter, a tray section comprising side and rear walls of double construction whereby air spaces are formed which are open at their upper and lower ends, the inner members of said walls projecting below the plane of the lower margins 70 of the outer walls and being bent inwardly and adapted to nest within the walls of another section, and a closure for the front of said section.

4. A grain sprouter, comprising a base 75 section adapted to contain a heating device, said base section being formed with ventilating ports, a drip pan being mounted in the upper portion of said base section and spaced from some of the walls thereof, a 80 plurality of tray sections separately formed and adapted to be mounted in series on said base section and adapted to carry grain trays with perforated bottoms, said tray sections having air spaces in their walls 85 open at their upper and lower ends and communicating throughout the height of said tray sections, the air spaces of the lowermost tray section communicating with the interior of the base section by means of the 90 spaces around said pan, and a movable top for the uppermost tray section.

Signed at Des Moines, in the county of Polk and State of Iowa, this 11 day of April, 1921.

CALVIN C. NEWPORT.
